MINING APPARATUS

2 Sheets-Sheet 2

by Leon E. Simmons *Att'y.*

UNITED STATES PATENT OFFICE.

LEON E. SIMMONS, OF CLAREMONT, NEW HAMPSHIRE, ASSIGNOR TO SULLIVAN MACHINERY COMPANY, A CORPORATION OF MASSACHUSETTS.

MINING APPARATUS.

Application filed June 16, 1924. Serial No. 720,420.

My invention relates to mining apparatus.

An object of my invention is to provide an improved mining apparatus. Another object of my invention is to provide an improved mining apparatus especially adapted to use in entry or room cutting where it is desirable for the machine to operate from its truck. A further object of my invention is to provide an improved mining apparatus of the mounted type having an independent propulsive mechanism in the form of a power drum mounted thereon adapted to wind in a cable secured at an extraneous point in advance or in the rear of the truck and having improved guiding means for the cable and an improved general arrangement of parts. These and other objects and advantages of my invention will, however, hereinafter more fully appear.

In the accompanying drawings I have shown for purposes of illustration one form which my invention may assume in practice.

In these drawings,

Fig. 1 is a plan view of a mining apparatus constructed in accordance with my improvement, the mining machine being removed therefrom and certain portions being broken away to facilitate illustration.

Fig. 2 is a side elevation of the mining apparatus shown in Fig. 1 with the mining machine in operative position thereon.

Fig. 3 is a detailed front end elevation partially in section, of a portion of my improved guiding arrangement.

In this illustrative construction I have shown a mining machine and truck of the same general character as that described and claimed in a pending application, Ser. No. 701,390, filed Mar. 24, 1924, which is the invention of one Morris P. Holmes, including, generally, a truck 1 provided with wheels 2 adapted to run along a trackway 3 and carrying thereon an adjustable body portion 4, vertically adjustable by means of manual adjusting means, generally designated 5, in such a manner that the body portion 4 is maintained parallel with the trackway in its different elevated positions. Mounted upon the adjustable body portion

4 is a complete mining machine, generally designated 6, of the bottom cutting type although it may be of any suitable type, but is herein of the well known chain fed room and pillar type, having a suitable driving motor, herein a pressure fluid actuated driving motor (not shown) and a projecting cutter bar 7 provided with an endless cutter bit carrying cutter chain 8 adapted to be circulated about the cutter bar in a well known manner. The machine 6 is mounted upon a swivel member 9, which is secured to the body portion 4, about which the mining machine is adapted to pivot to cut an arcuate kerf in the working face of the coal through any suitable power driving connections from the driving motor. Mounted upon the rear end of the adjustable body portion 4 of the truck is provided a propulsive mechanism of improved form adapted to move the mining apparatus relative to the trackway.

In my improved construction it will be noted that I have mounted on the body portion 4 a propulsive or reeling mechanism generally designated 10 which is adapted to wind in a flexible member, herein a cable 11. This reeling mechanism, which likewise is a Holmes invention, comprises a unidirectional pressure fluid actuated driving motor, a portion of which is indicated at 10', disposed within the drum of the reeling mechanism, the rotation of the drum being controlled by a reaction mechanism, generally designated 12 including a brake band 13 and brake band applying mechanism including a lever 14 pivoted at 15 to a downwardly projecting rod 16, which is in turn pivoted at 17 to a crank 18 adapted to be operated by a lever 19 disposed adjacent the operating side of the truck. The drum is provided with a brake band 20, having a suitable operating handle 21, which is adapted to control or brake the rotation of the drum when the reaction control mechanism 12 is released, for instance, when the mining apparatus is moving down a trackway of a steep gradient. Pressure fluid is adapted to be admitted to the drum driving motor

through a pipe connection 22 under the control of a throttle valve 23, which pipe connection communicates through a pipe connection 24 leading in any suitable manner 5 to a hose reel 25 suitably mounted on the rear end of the adjustable body portion 4 and which is adapted to wind in or pay out a hose 26 as the mining apparatus moves along the trackway and through which hose 10 pressure fluid passes from any suitable source of supply. A guiding mechanism, generally designated 27, guides the hose as it is wound in or paid off from the reel.

In my improvement it will be noted that 15 when it is desired to move the mining apparatus forwardly along the trackway the cable 11 is passed from the top of the drum of the reeling mechanism 10, beneath a guide roll or sheave 28, slidably mounted on 20 a transversely extending horizontal shaft 29 supported by suitable standards 30 carried upon the body portion 4, and forwardly over a guide roll 31, journaled on a transversely extending horizontal shaft 32, forwardly beneath the mining machine and its cooperating parts over a transversely extending horizontal guide roll 33, journaled as at 34 in bearing members 35 suitably secured as by bolts to transversely extending plate members 36 which are in turn suitably secured to longitudinally extending parallel angle irons 37 forming a portion of the body portion 4 of the truck. The cable 11 is then guided laterally over the roll 33 by means of guide 30 sheaves 38 rotatably mounted upon vertical studs 39 disposed in the same vertical plane as the axis of the guide reel 33, the cable then passing forwardly along the trackway to a suitable stationary abutment, for instance, a rail clamp or the like. When the cable is in this position the throttle valve 23 is manipulated by the operator permitting pressure fluid to pass through the hose 26, the reel connections, and pipe connections 24 and 22 to the drum driving motor. The operator then manipulates the handle 19 which applies pressure to the brake band 13 operating the reaction control mechanism 12, causing the drum to be rotated in a clockwise direction as viewed in Fig. 2, winding in the cable and consequently moving the mining apparatus forwardly along the trackway. As the cable is wound onto the drum, the guide sheave 28 moves back and forth along 55 the shaft 29 causing the cable to be wound evenly onto the drum in the usual manner.

When it is desired to move the mining apparatus rearwardly along the trackway, the cable extends beneath the guide sheave 28, over the guide roll 31, around one of the guide sheaves 38, and is then extended transversely of the truck around a guide sheave 40, journaled on a vertical stud 41 suitably secured to a detachable bracket member 42 60 which is provided with an inwardly pro-

jecting cylindrical portion 43 adapted to be inserted in a bore 44 formed in a carrier member 45 suitably secured to the cross plate members 36 of the truck. The bracket member 42 is provided with an inwardly projecting lug 45' adapted to engage the side of the carrier member 45 thereby preventing rotation of the bracket about the cylindrical portion 43. The bracket member is also provided with an upwardly extending arcuate 75 guiding portion 46 which prevents the cable from dropping off the sheave when the cable is slackened. The cable then passes from the sheave 40 rearwardly along the side of the mining apparatus around a guide sheave 80 47, similar to the sheave 40, rotatably mounted upon a stud 48 suitably carried by a bracket 49 which is adjustably carried by means of a set screw connection upon a bracket 50 suitably secured to the truck body portion 4, and the cable then passes transversely of the truck and around the guide sheave 51 rotatably mounted upon a vertical stud 52 carried by a bracket 53 suitably secured to the truck frame. It will herein be noted that the bracket 49 may be swung in out of the way when not in use, if desired, by simply releasing the set screw. The cable then passes rearwardly along the trackway to a suitable extraneous stationary abutment. 90 The drum of the reeling mechanism 10 is then again actuated, thus reeling in the cable, and consequently moving the mining apparatus rearwardly along the trackway.

As a result of my improvement it will be noted that I have provided an improved mining apparatus propulsive mechanism having an independent driving motor which is of exceedingly simple and compact form and which may be applied to a truck of 100 standard construction with a minimum of change. It will further be noted that I have provided an improved unidirectional propulsive mechanism adapted to move the mining apparatus in either direction along the trackway by means of a flexible cable and which includes improved guiding means for the cable.

While I have in this application described one form which my invention may assume 115 in practice, it will be understood that this form of the same is shown for purposes of illustration and that the invention may be modified and embodied in various other forms without departing from its spirit or 120 the scope of the appended claims.

What I claim as new and desire to secure by Letters Patent is:

1. In a mining apparatus, a wheeled truck 125 adapted to support a mining machine, a propulsive mechanism therefor independent of such machine including a power drum and a cooperating flexible cable cooperating therewith, said drum being mounted on said truck between the ends of the latter, and means 130

carried at the opposite ends of said truck and at opposite sides of said drum for guiding said cable during movement of said truck.

2. In a mining apparatus, a wheeled truck, adapted to support a mining machine, a propulsive mechanism therefor independent of such machine including a power drum and a cooperating flexible cable cooperating therewith, and means to guide said cable during movement of said truck in opposite directions including guide sheaves carried at the opposite ends of said truck and at opposite sides of the transverse zone in which said drum lies.

3. In a mining apparatus, a wheeled truck adapted to support a mining machine, a propulsive mechanism therefor independent of such machine including a power drum and a flexible cable cooperating therewith, and means to guide said cable during movement of said truck in opposite directions including guide sheaves journaled on vertical axes at the opposite ends of said truck and at opposite sides of the transverse zone in which said drum lies.

4. In a mining apparatus, a wheeled truck adapted to support a mining machine, a propulsive mechanism therefor independent of such machine including a power drum and a cooperating flexible member cooperating therewith, and means for guiding said flexible member forwardly and rearwardly during movement of said truck including a plurality of guiding sheaves carried by said truck at opposite sides of the transverse zone in which said drum lies.

5. In a mining apparatus, a wheeled truck having a mining machine thereon, a propulsive mechanism therefor including a power winding drum and a cable cooperating therewith, and means for guiding said cable including a plurality of sheaves disposed adjacent the longitudinal center of said truck and at each end thereof.

6. In a mining apparatus, a wheeled truck having a mining machine thereon, and independently powered propulsive mechanism carried by said truck including a winding drum and a cable cooperating therewith, and means for guiding said cable including a plurality of sheaves journaled on vertical axes and disposed adjacent the longitudinal center line of said truck and at each end thereof.

7. In a mining apparatus, a wheeled truck having a mining machine thereon, and independently powered propulsive mechanism carried by said truck including a winding drum and a cooperating cable, and means for guiding said cable including a plurality of sheaves disposed at each corner of one side of said truck and at each end thereof and one of which is rotatable on an axis bearing constantly the same relation to the truck.

8. In a mining apparatus, a wheeled truck having a mining machine thereon provided with a driving motor, means independent of said motor for propelling said truck relative to a trackway including a power drum and a cooperating cable, and means for guiding said cable including a plurality of transversely disposed horizontal rolls and a plurality of sheaves rotatable on vertical axes adjacent the major axis of said truck. 75

9. In a mining apparatus, a wheeled truck having a mining machine swiveled thereon provided with a driving motor, means independent of said motor for propelling said truck relative to a trackway including a power drum and a cooperating cable, means for guiding said cable forwardly beneath the mining machine and the swivel to a point in advance of the truck, and means for guiding the cable outwardly transversely of the truck, 80 rearwardly along the truck, inwardly transversely of the truck, and rearwardly to a point in the rear of the truck. 85

10. In a mining apparatus, a wheeled truck having a mining machine thereon provided with a driving motor, means independent of said motor for propelling the truck relative to a trackway including a power drum and a cooperating cable, and means for guiding said cable forwardly beneath said mining machine to a point in advance of the truck including a plurality of transversely disposed horizontal rolls and cooperating sheaves journaled on adjacent vertical axes. 90 95

11. In a mining apparatus, a wheeled truck, a mining machine thereon provided with a driving motor, means independent of said motor for propelling the truck relative to a trackway including a power drum and a cooperating cable, and means for guiding said cable forwardly or rearwardly relative to said truck including a plurality of guide sheaves, at least one of which is laterally adjustable about a spaced pivot. 100 105

12. In a mining apparatus, a wheeled truck 110 adapted to support a mining machine during cutting, a propulsive mechanism therefor including a power drum rotatable upon an axis fixed as to longitudinal movement relative to said truck, and a cooperating flexible cable cooperating with said drum, and rotatable guiding means carried at the opposite ends of said truck and nearer the proximate end in each case than said drum for guiding said cable during movement of said truck. 115 120

13. In a mining apparatus, a wheeled truck adapted to support a mining machine during cutting, a propulsive mechanism therefor including a power drum rotatable upon an axis fixed as to longitudinal movement relative to said truck, and a cooperating flexible cable cooperating with said drum, and means carried at the opposite ends of said truck and nearer the proximate end in each case than said drum for guiding said cable during 125 130

movement of said truck including guide sheaves journaled on vertical axes at the opposite ends of said truck.

14. In a mining apparatus, a wheeled truck having a mining machine thereon, and independently powered propulsive mechanism carried by said truck including a winding drum and a cooperating cable, means for

guiding said cable including a plurality of sheaves disposed at each corner of one side 10 of said truck and at each end thereof, said winding drum being disposed in a transverse zone intermediate the corner sheaves which are at opposite ends of the truck.

In testimony whereof I affix my signature.

LEON E. SIMMONS.
